DISPLAY DEVICE

John Richard Pollard, Amsterdam, N. Y., assignor
to Mohawk Carpet Mills, Inc., Amsterdam,
N. Y., a corporation of New York

Application October 30, 1948, Serial No. 57,508

6 Claims. (Cl. 40—126)

1

This invention relates to display apparatus for use in exhibitions, show rooms, etc., and is concerned more particularly with a novel device for showing the methods and looms used in weaving pile fabrics, such as carpets of various kinds.

Pile fabrics employed as floor coverings are of various constructions and are woven on looms of different kinds. When such floor coverings are on exhibition before the general public, few visitors are aware of the differences distinguishing the several basic types of weave or understand the reasons why one construction has advantages over another for specific purposes. While the distinctive features of the several constructions may be readily explained graphically, it has been found that display devices, which include characteristic portions of the respective looms and of the fabrics made thereon, are more effective in conveying information than the usual diagrams, brochures, etc.

The present invention is, accordingly, directed to the provision of novel apparatus for displaying the methods and looms used in the production of pile fabric floor coverings. The new devices include the warp threads present in the fabrics and also structures simulating those employed on actual looms. While the devices are of simple construction, they demonstrate differences in weaves and looms in a manner easily understood and are a center of interest, wherever they are exhibited.

For a better understanding of the invention, reference may be made to the accompanying drawings, in which

Fig. 1 is a view in perspective of one form of 35 the new device used for displaying a Wilton fabric and the loom used for weaving it;

Fig. 2 is a view of the device of Fig. 1 in side elevation;

Fig. 3 is a sectional view of the line 3—3 of 40 Fig. 2;

Fig. 4 is a view in perspective of a form of the device used for displaying an Axminster fabric and loom;

Fig. 5 is a side elevational view of the device 45 of Fig. 4;

Fig. 6 is a sectional view on the line 6—6 of Fig. 4; and

Fig. 7 is a front elevational view on an enlarged scale of a portion of the device of Fig. 4.

The display device of Fig. 1 includes a base 10 and a panel 11 rising therefrom, the base and panel being made of any suitable building material. A pair of side members 12 are attached to the base and the front face of the panel and

project forwardly from the panel in spaced parallel relation. The members 12 simulate the sides of a loom and a beam 13 connects the members near their upper ends adjacent their free edges. 10 An arbor 14 is mounted in openings in members 12 near their lower ends and a web 15 of Wilton carpet is rolled on the arbor and extends upwardly from the roll and over the beam 13. The carpet is so rolled that the pile surface in the portion of the fabric between the roll and the beam faces forward, so that the pattern is clearly visible.

The fabric terminates near the rear edge of the beam and the warp threads 16 only of the 15 fabric continue from the beam to the face of the panel. The warp threads diverge in upper and lower sheets from the beam to the panel, so that they resemble a warp shed employed in weaving, and the rear ends of the threads are secured to 20 the panel and may pass through openings in the panel and be affixed to the rear face thereof.

The upper rear corners of the members may be cut away to provide openings 17, through which extends a guideway 18 attached to the side 25 members below the warp threads 16 and projecting laterally a substantial distance beyond them. The guideway simulates the raceway for the shuttle of a loom and a bobbin 19 filled with yarn may be placed at one end of the raceway to suggest a shuttle. A pair of sticks 20 are attached to the outer faces of side members 12 on ears 21 and extend upwardly through guide loops 22 attached to the members and through openings at the ends of the guideways. The sticks 20 resemble the picker sticks of a loom, and the loops 22 are similar to the straps by which the picker sticks are operated on a real loom. A reed 23 is attached to the rear of the guideway and extends upwardly and rearwardly to the front face of the panel, the warp threads 16 passing through the dents of the reed.

In patterned Wilton fabrics, the design in the pile surface is formed of colored pile warp yarns, which are raised over wires during the weaving operation by a Jacquard mechanism. The pile warps 16 are, accordingly, of different colors and, in order to suggest the beam, from which such warps are supplied during weaving, the area 24 of the panel above the reed may carry vertical lines of different colors to simulate the appearance of such a beam and of the yarns passing therefrom to the reed.

The device shown in Fig. 4 is used to demonstrate an Axminster fabric and loom and comprises a base 25, a panel 26 rising therefrom, and

spaced side members 27 extending forwardly from the front face of the panel. The side members are connected by a beam 28 and an arbor 29 is supported in the members and carries a roll of carpet 30. The carpet extends upwardly and over the beam and, beyond the beam, the weft threads of the fabric are omitted and the warp threads 31 extend toward the panel in divergent upper and lower sheets and are connected thereto.

In Axminster weaving, the pile is produced by dipping lengths of pile yarn between the stuffer and binder warps, binding in such pile yarns by weft shots, and then cutting the yarns to leave in the fabric pile tufts looped about weft shots. The pile yarns are carried on spools, each spool being used for forming a row of tufts, and each spool is preliminarily wound with yarns of the colors required by the pattern in the row of tufts, for which the spool is to be employed. Each spool is carried in a tube frame having tubes, one for each yarn on the spool, and the yarns pass through individual tubes and project therefrom. In the operation of the loom, the tube frames mounted on a carrier are brought successively to the weaving station, at which place, the frame in position is removed from the carrier, lowered to dip its tubes and yarns between the warps, and, after the binding in and cutting of the yarns, is restored to the carrier.

The device shown in Fig. 4 includes a tube frame 32 similar to those in actual use and mounted in ears 33 attached to the front face of the panel above the upper sheet of warp threads 31. The frame carries a spool 34 wound with yarns of different colors and has a row of tubes 35, through which the individual yarns pass. The yarns extending out of the tubes are led down between the warp threads 31 and their lower ends are secured to a cross-bar 36 extending between the side members 27. In an Axminster loom, the weft threads are inserted by a needle, instead of by a shuttle. Accordingly, the device of Fig. 4 does not include a guideway or sticks similar to sticks 20, and a needle or any simulation thereof is omitted because of the length of such a needle.

In both of the display devices shown, the panel rises a considerable distance above the base and the upper portion thereof provides spaces on which illustrations 37, samples of fabrics, advertising material, etc. may be placed.

I claim:

1. A display device, which comprises a base, a panel rising from the base, a pair of side members attached to the base and extending forwardly from the panel in spaced parallel relation, a beam extending between the side members near the top thereof, an arbor extending between the side members near the lower ends thereof and adapted to support a web of carpet rolled on the arbor and extending upwardly to and rearwardly over the beam, and warp threads only of the carpet extending rearwardly from the beam to the panel in divergent sheets with the rear ends of said threads attached to the panel.

2. A display device, which comprises a base, a panel rising from the base, a pair of side members attached to the base and extending forwardly from the panel in spaced parallel relation, a beam extending between the side members near the top thereof, an arbor extending between the side members near the lower ends thereof and adapted to support a web of carpet rolled on the arbor and extending upwardly to and rearwardly

over the beam, warp threads only of the carpet extending rearwardly from the beam to the panel in divergent sheets with the rear ends of said threads attached to the panel, a pair of sticks attached to the outer faces of the respective side members near the lower ends thereof and extending upwardly, and a guideway connecting the sticks and lying adjacent to and below the lower sheet of warp threads.

3. A display device, which comprises a base, a panel rising from the base, a pair of side members attached to the base and extending forwardly from the panel in spaced parallel relation, a beam extending between the side members near the top thereof, an arbor extending between the side members near the lower ends thereof and adapted to support a web of carpet rolled on the arbor and extending upwardly to and rearwardly over the beam, warp threads only of the carpet extending rearwardly from the beam to the panel in divergent sheets with the rear ends of said threads attached to the panel, a pair of sticks attached to the outer faces of the respective side members near the lower ends thereof and extending upwardly, and a guideway connecting the sticks and lying adjacent to and below the lower sheet of warp threads, the guideway having openings at its ends through which the sticks extend.

4. A display device, which comprises a base, a panel rising from the base, a pair of side members attached to the base and extending forwardly from the panel in spaced parallel relation, a beam extending between the side members near the top thereof, an arbor extending between the side members near the lower ends thereof and adapted to support a web of carpet rolled on the arbor and extending upwardly to and rearwardly over the beam, warp threads only of the carpet extending rearwardly from the beam to the panel in divergent sheets with the rear ends of said threads attached to the panel, a pair of sticks attached to the outer faces of the respective side members near the lower ends thereof and extending upwardly, a guideway connecting the sticks and lying adjacent to and below the lower sheet of warp threads, and a reed extending upwardly from the guideway and meeting the panel above the upper sheet of warp threads, the threads passing through the dents of the reed.

5. A display device, which comprises a base, a panel rising from the base, a pair of side members attached to the base and extending forwardly from the panel in spaced parallel relation, a beam extending between the side members near the top thereof, an arbor extending between the side members near the lower ends thereof and adapted to support a web of carpet rolled on the arbor and extending upwardly to and rearwardly over the beam, warp threads only of the carpet extending rearwardly from the beam to the panel in divergent sheets with the rear ends of said threads attached to the panel, a pair of sticks attached to the outer faces of the respective side members near the lower ends thereof and extending upwardly, a guideway connecting the sticks and lying adjacent to and below the lower sheet of warp threads, the guideway having a longitudinal channel in its upper face, and a yarn bobbin in the guideway.

6. A display device, which comprises a base, a panel rising from the base, a pair of side members attached to the base and extending forwardly from the panel in spaced parallel relation,

a beam extending between the side members near the top thereof, an arbor extending between the side members near the lower ends thereof and adapted to support a web of carpet rolled on the arbor and extending upwardly to and rearwardly over the beam, warp threads only of the carpet extending rearwardly from the beam to the panel in divergent sheets with the rear ends of said threads attached to the panel, a tube frame mounted on the panel above the upper sheet of warp threads, a spool wound with yarns mounted in the frame, the ends of said yarns extending through the tubes on said frame and downwardly between the warp threads, and a cross-bar carried by the side members below the warp threads, 15

the lower ends of the yarns being secured to the cross-bar.
